Inventor,

Leonard Atwood;

By *A. B. Uppham*,

Attorney.

UNITED STATES PATENT OFFICE.

LEONARD ATWOOD, OF BOSTON, MASSACHUSETTS.

WOVEN HOSE.

1,365,809.

Specification of Letters Patent. Patented Jan. 18, 1921.

Application filed November 22, 1919. Serial No. 339,810.

To all whom it may concern:

Be it known that I, LEONARD ATWOOD, a citizen of the United States, and a resident of Boston, in the county of Suffolk and Commonwealth of Massachusetts, have invented certain new and useful Improvements in Woven Hose, of which the following is a full, clear, and exact specification.

The object of this invention is the construction of a wire-wound hose wherein the wire shall be incapable of separation from and of shifting with respect to the rubber and fabric composing the remainder of the hose. In the case of wire-strengthened woven hose previously in use, any bending thereof will so displace the helically disposed wire as to cause the latter to remain permanently displaced and to thereby badly affect the hose both as a matter of appearance and of utility.

To accomplish this I provide a strand for helical application to the hose being woven, which strand is composed of a plurality of wires, preferably two, so intertwined with fibrous material as practically to conceal the wires. When this strand is woven into the hose and treated with rubber solution these fibers will so strongly anchor the wires in place that no amount of bending and twisting of the hose can displace the same.

In the drawings forming part of this specification, Figure 1 is a side view of a section of hose embodying my improvement. Fig. 2 is a sectional view of a part thereof. Fig. 3 is a side view of a length of the composite strand used in the manufacture of the hose. Fig. 4 is an exaggerated view of a pair of wires twisted together and having a part thereof supplied with fibrous material.

As shown in Fig. 4, the two or more strands of wire 1 are twisted together with fibrous material 2 gripped thereby and appearing substantially as illustrated in Fig. 3.

The hose is woven in substantially the customary manner, the warp 3 extending longitudinally, and the composite strand 1, 2 is the weft or filling, as shown at the left hand part of Fig. 1 and in Fig. 2. After the weaving, a coating of rubber 4 is applied, as indicated in Fig. 1, in a well known manner, and then vulcanized. This rubber thor-

oughly embeds itself in the inter-fiber spaces, so that after vulcanization it is impossible for the wires 1 to detach themselves from the warp or the rubber coating. 55

At the same time, the wire helix within the hose greatly strengthens it against either bursting because of excessive inner pressure, or of being crushed by external compression.

This hose can be coated or impregnated 60 by rubber in a well known manner, or by means of the mechanism set forth in my companion applications Serial Nos. 308,625 and 308,626.

What I claim is:

1. A fabric having warp and weft, the weft being composed of a strand of wire and fiber secured together.

2. A fabric having warp and weft, the weft being composed of a plurality of wires 70 having fiber secured thereto.

3. A fabric having warp and weft, the weft being composed of a plurality of wires twisted together and of fibers secured thereto. 75

4. A fabric having warp and weft one of which is composed of fiber and a plurality of wires twisted together to attach said fiber thereto.

5. A hose having a composite helix about 80 it, the helix comprising fibers and a plurality of wires twisted together to attach said fibers thereto.

6. A hose having a composite helix about 85 it, comprising fibers and a plurality of wires twisted together to attach said fibers thereto, and a rubber coating engaging said wire and fiber.

7. A hose woven with a warp and weft, the weft comprising a plurality of wires 90 twisted together and fibers confined thereto, and a rubber coating incorporated therewith.

8. A hose woven with a warp and weft, the weft comprising two wires twisted together and fibers attached thereto by the 95 clamping action of the twisted surfaces, and a rubber coating incorporated therewith.

In testimony that I claim the foregoing invention, I have hereunto set my hand this 19th day of November, 1919.

LEONARD ATWOOD.
